UNITED STATES PATENT OFFICE.

HARRY R. LIVINGSTON, OF WASHINGTON, DISTRICT OF COLUMBIA.

VERTICAL-FILE-FOLDER ACCESSORY.

Application filed February 2, 1921, Serial No. 441,923. Renewed March 1, 1923.

To all whom it may concern:

Be it known that I, HARRY R. LIVINGSTON, a citizen of the United States, residing at Washington, in the District of Columbia, 5 have invented certain new and useful Improvements in Vertical-File-Folder Accessories, of which the following is a specification.

This invention relates to certain new and 10 useful improvements in vertical file folders.

Vertical file folders are usually constructed with one side longer than the other so as to provide space for the entry of the desired indicia, such, for instance, as the 15 name, number, etc., but as these folders are sometimes, even quite often, called upon to hold an excessive number of papers, the folder sags and the short side is thus gradually pulled down so as to leave much 20 greater space showing on the longer side, and, furthermore, the papers are apt to double up, resulting in much inconvenience, as has been found from actual experience. Furthermore, as the fold or connection be- 25 tween the two sides is generally flexible, and sometimes with a gusset, the papers are at all times liable to double up, and the present invention has for its object primarily to provide simple and efficient means for over- 30 coming this objection. By its employment I am enabled to prolong the life of the ordinary file, as well as providing a rigid bottom therefor adapting it for holding many 35 more papers than for which it was originally intended, and this without changing the relative positions of the upper edges of the longer and shorter sides.

Other objects and advantages of the in- 40 vention will hereinafter appear and the novel features thereof will be particularly pointed out in the appended claims.

The invention is clearly illustrated in the 45 accompanying drawings, which, with the numerals of reference marked thereon, form a part of this specification, and in which—

Figure 1 is a perspective view of a vertical file folder showing my invention ap- plied.

Figure 2 is a perspective detail showing 50 the manner of applying the rigid strip with its gummed portions.

Figure 3 is a perspective view of the old 55 form of file folder, showing how it sags under the weight of the papers and how the papers are apt to curl.

Figure 4 is a perspective view showing the old folder being cut at the bottom or fold.

Figure 5 is a perspective view of a folder 60 showing a modified form of rigid bottom with its attaching strips.

Figure 6 is a perspective detail showing the manner of applying this form of strip.

Figure 7 is a perspective view of the form 65 of strip employed in Figures 5 and 6.

Like numerals of reference indicate like 70 parts throughout the different views.

Referring first to Figure 3, 1 designates the old form of vertical file folder in which 75 2 is the front or shorter side and 3 the longer side, these two parts being connected at the lower edge by the fold or bend 4 which forms the bottom of the folder. The sides 2 and 3 are normally so proportioned as to leave a space at the upper end of the longer side 3 for the name and number or 80 other indicia. Ordinarily the upper edge of the front side 2 normally extends to about the dotted line indicated on the member 3, but when papers 5 are placed in the folder 85 in any great number the folder sags so that the front or shorter side 2 is gradually caused to drop until it assumes the position seen in Figure 3 and the papers 5 are apt to follow the curvature of the bottom or fold 4 and thus curl up. This is very objection- 90 able and in order to overcome this I provide the means now to be described.

When the folder is called upon to hold an 95 excessive number of papers, the folder is cut along the normal fold line, as seen in Figure 4, by knife or other suitable imple- 100 ment, as shown in said figure, and then there is applied a base comprising a strip 6 of press-board or analogous material which is pre-formed with a gummed strip 7 secured to the under side thereof and pro- 105 jecting beyond the edges thereof to form flaps 8, 8, as seen clearly in Figure 2. The adjacent edges of the two portions 2, 3 of the folder, which have been separated as 110 above described in connection with Figure 4, are placed upon the portions 8, 8 with their edges abutting the edges of the strip 6, and the gummed faces of the portions 8, 8 are then moistened and the said edges folded up together with the members 2 and 3 and pressure applied so that the gummed strips 8, 8, are caused to adhere to the outer faces of the two portions 2 and 3. The folder then assumes the form seen in Figure 110

1, the member 6 constituting a rigid bottom for the folder and the relative positions of the members 2 and 3 are unchanged from their original position so that the member 5 3 projects above the top edge of the member 2 the same distance as originally.

In Figures 5, 6 and 7 I show the same improvement carried a step further in that I provide the central strip 9 of press-board 10 or the like of a length corresponding to the length of the members 2 and 3, as indicated by dotted lines in Figure 7, and with the extensions 10, 10 which are adapted to form rigid ends to the folder when the strip is 15 applied, as will be readily understood. In this form the strip 9 has secured to its under side the piece 11 which may be of muslin or the like or a sufficiently tough and pliable paper well adapted for the purpose, the same 20 being extended beyond the side edges of the strip 9 to constitute the side flaps 12, 12 which are gummed, as in the form shown in Figure 1. 13, 13 are side flaps for the portions 10, 10, the same being notched angularly, as seen at 14, adjacent the ends of the 25 main portion of the strip 9 so that when applied in the same manner as hereinbefore described in connection with the strip seen in Figures 1 and 2, the portions 10, 10 extend up at the ends of the folder and form rigid closures at the bottom of the opposite ends, it being understood that the portions 12, 12 are folded up against the outer faces of the portions 2 and 3 of the folder and the 30 portions 10 of the center strip are folded up inside of the edges of the portions 2 and 3 at the ends of the flaps 13 then bent over and secured to the outer faces of the portions 2 and 3.

40 By this means I am enabled to materially enhance the value and usefulness of the folder and avoid the necessity of having to supply new indicia at the top thereof.

45 While designed primarily for use in connection with folders which have already been in use and have the indicia supplied thereto, in the manner hereinbefore described, it is evident that the strips with their gummed portions may be employed in 50 the original make-up of the folder, but it is to be understood that the strips themselves are to constitute a complete article of manufacture applicable to the uses hereinbefore described.

55 Modifications in details may be resorted to without departing from the spirit of the invention or sacrificing any of its advantages.

What is claimed as new is:—

60 1. As an improved article of manufacture, a strip for use in the repair of a vertical file holder, the same comprising a rigid piece of material to be applied between the edges of a severed folder to constitute the bottom

of the repaired file folder, and a flexible 65 strip applied to said piece and having side flaps extended beyond the edges of said piece for attachment to the separated side members of the file folder to increase the capacity 70 of said folder.

2. As an improved article of manufacture, a strip for use in the repair of a vertical file folder, the same comprising a substantially rigid base member and a flexible strip secured to one face thereof and having flaps 75 extended beyond the side edges thereof and gummed for attachment to adjacent edges of the separated side members of the folder to increase the capacity of the folder while retaining the relative positions of the upper edges of the side members of the folder.

3. A vertical file folder repair strip, the same comprising a substantially rigid base member and a flexible strip secured thereto and having flaps extended beyond the side edges thereof and gummed, the said base member having extensions adapted to form 85 closures for the ends of the file folder.

4. A vertical file folder repair strip, the same comprising a substantially rigid base member and a flexible strip secured thereto and having flaps extended beyond the side edges thereof and gummed, the said base member having extensions adapted to form 90 closures for the ends of the file folder, and gummed flaps on said extensions.

5. A vertical file folder repair strip, the same comprising a substantially rigid base member and a flexible strip secured thereto and having flaps extended beyond the side edges thereof and gummed, the said base member having extensions adapted to form 100 closures for the ends of the file folder, and gummed flaps on said extensions, the last-named flaps being angularly notched adjacent the first-named flaps.

6. A vertical file folder comprising back and front members, a substantially rigid bottom and a strip of pliable material secured to the under face of the bottom and embracing and secured to the outer faces of the back and front members of the folder, said bottom having integral extensions at the ends provided with gummed side flaps, said extensions being disposed between the adjacent faces of the back and front members and the side flaps of said extensions embracing and secured to the outer faces of the side members.

7. The method of enlarging the capacity 110 of a vertical file folder which consists in severing the folder, interposing between the severed edges thereof a substantially rigid base and securing said base to the adjacent 115 severed edges of the folder.

In testimony whereof I affix my signature.

HARRY R. LIVINGSTON.
